UNITED STATES PATENT OFFICE.

WALTER A. BEHRENS, OF NEW YORK, N. Y., ASSIGNOR TO W. R. OSTRANDER & COMPANY, OF NEW YORK, N. Y., A CORPORATION OF NEW YORK.

MECHANICAL MOVEMENT FOR ELECTRIC SWITCHES, &c.

1,368,992.

Specification of Letters Patent. Patented Feb. 15, 1921.

Application filed December 6, 1919. Serial No. 343,055.

To all whom it may concern:

Be it known that I, WALTER A. BEHRENS, a citizen of the United States of America, residing at Brooklyn, N. Y., have invented 5 new and useful Mechanical Movements for Electric Switches, &c., of which the following is a specification.

The main object of my invention is to provide a simple and inexpensive mechanism by 10 which rotary motion can be transformed into intermittent oscillating movement with a snap action, such for instance, as is required in electric switches of the key operated type for sockets, etc.

15 The invention contemplates the employment of a shaft or spindle which may be rotated in either direction. The swinging or oscillating member, which in a switch would constitute the contact or switch arm, 20 is connected to the shaft or spindle by a special mechanism, the main feature of which in its preferred form is what may be termed a wabbling piece connected at one end to the shaft, connected at the other end to the 25 swinging member by means which includes a spring and guided intermediate its ends by a slotted plate. I have shown three forms of mechanisms embodying the broad principles of the invention.

30 Figure 1 is a plan view of one form of mechanism embodying the improvements of my invention.

Fig. 2 is a side view of the same.

35 Fig. 3 is a side view of the frame which supports the rotating shaft and swinging member, the view being taken from the side opposite to that of Fig. 2.

40 Fig. 4 is a transverse sectional view on the plane of the line 4—4 of Fig. 2 showing the wabbling member.

Fig. 5 is a plan view of another form of mechanism.

Fig. 6 is a side view of the same.

45 Fig. 7 is a perspective view of the wabbling member of Figs. 5 and 6.

Fig. 8 is a transverse sectional view on the plane of the line 8—8 of Fig. 6.

Fig. 9 is a plan view of another form.

50 Fig. 10 is a side view of the same showing the parts in one position.

Fig. 11 is a side view showing the parts in another position.

Fig. 12 is a perspective view of one of the connecting levers of the mechanism of the latter form. 55

Fig. 13 is an end view of the frame which supports the moving parts.

The oscillating or swinging member 15 is pivotally carried by a plate 16, and provided with a lug 17 which projects laterally 60 and is adapted to swing between the stops 18—18.

The frame which supports the moving parts of the mechanism is in its preferred form of sheet metal, having the side plate 65 16, base plate 19, and the two bearing plates 20—20 for rotatably supporting the spindle or shaft 21.

The spindle 21 is suitably supported in the bearing plates 20—20 and carries two 70 cam-like members 22 and 23 which rotate with the shaft or spindle, but are spaced apart from each other endwise sufficiently to allow for the plate 24 of the wabbling member. The latter has a finger 25 guided 75 in a slot 26 in a plate 16. The end of the finger 25 is connected to the lug 17 by means of a helical spring 27 which is under tension and which tends to draw the lug and finger toward each other. The parts are so 80 proportioned and arranged with respect to each other that the arm 15 is held in the position of Fig. 2 under tension of the spring 27 when the finger 25 is in the outer end of the slot 26. When the shaft 21 is rotated in either direction, the cams 22 and 23 twist the plate 24, so that the finger 25 is shifted to the rear end of the slot 26. This causes the spring 27 to pull on the opposite side of the axis of the arm 15. As soon as 85

the pull is sufficient to overcome the ordinary friction and inertia of the arm 15, the arm snaps up until the lug 17 strikes the right hand stop 18. In the form shown, in order to snap the arm 15 up, it is necessary 90 to turn the shaft 21 approximately 180° when turning it in a right hand direction, but only necessary to turn it approximately 95 90° when turned in a left hand direction, but successive rotation in either direction of 100 180° is necessary for repeated action.

When the mechanism is used for a switch, the parts are usually mounted on an insulating base such as 28, and provided with one

or more contacts such as 29 and 30, depending on whether single break or double break mechanism is desired.

In the form shown in Figs. 5 to 8, the base plate 19' of the supporting frame carries two bearing members 20' and 20'' for the shaft 21'. In this case, the arm 15' is pivotally carried by the side plates 16', and adapted to swing between the stop shoulders 18' and 18''. In this case, the end of the shaft 21' is bent slightly to one side and the wabbling member has a sleeve 24' loosely fitting on this bent end of the shaft. The finger 25' of the wabbling member is guided in the slot 26' and connected by a spring 27' to the lug 17' of the arm 15'. The action is very similar to that of the form shown in Figs. 1 to 4 inclusive, but in this case, in order to snap the arm 15' 20 from the position shown in Fig. 6, it is necessary to turn the key spindle or shaft about 180° in a right hand direction or about 180° in a left hand direction.

In the form shown in Figs. 9 to 13 inclusive, the oscillating or swinging arm 15^a is double and therefore somewhat stiffer. The base plate 19^a of the frame carries supporting arms 16^a and 16^b for the swinging member and bearing plates 20^a and 20^b for the spindle or shaft 21^a. The wabbling mechanism is the same as that shown in the first form, and has a finger 25^a guiding in the slot 26^a. In this case however the finger 25^a is connected to the arm 15^a through the medium of a lever 31, link 32, and spring 27^a. The lever 31 has a notch 33 through which the end of the wabbling finger 25^a projects. The link 32 has one end hooked into a notch or recess 34 in one arm of the lever 31, and has the other end hooked into a slot 35 in one of the arms of the swinging member 15^a. The spring 27^a is centered at one end by the lug 36 in the side of the arm 15^a, and presses at its opposite end 40 against one end of the link 32, so as to constantly assert a pressure on the link tending to pull against the lever 31. In the position shown in Fig. 10, the arm 15^a presses against the stop 18^a, and in the position of Fig. 11, the arm presses upwardly against the stop 18^a (see Fig. 13). This form of mechanism requires substantially 180° revolution of the shaft in either direction to snap the contact arm 15^a. The link and 50 spring mechanism of Figs. 9, 10, and 11

is claimed in my companion application #343,056.

I claim:

1. Mechanism of the character described, comprising a frame including a slotted plate 60 and swinging arm supported by said plate, a rotary shaft having bearings in said frame, a wabbling member connected to said shaft and having a part guided in said slotted plate and means of connection between said wabbling member and said arm including a spring whereby upon rotation of said shaft said arm may be snapped in one direction or the other.

2. Mechanism of the character described, 70 comprising a pivoted arm and rotary shaft, a wabbling member connected to one end of said shaft and guided from the opposite end of said member, stops for said arm and a spring connecting said wabbling member 75 and said arm.

3. Mechanism of the character described, including a frame, a rotary shaft carried thereby, a pivoted arm carried by said frame, a wabbling member connected to one 80 end of said shaft and guided at the other end by said frame and means of connection between said wabbling member and said arm including a spring for moving the arm with a snap action when the shaft is rotated.

4. Mechanism of the character described, including a plate having a guide, an arm pivoted to said plate, stops for limiting the movement of said arm, a rotary shaft, a wabbling member connected to said shaft 90 and having a finger engaging said guide and a spring connection between said finger and said arm.

5. Mechanism of the character described, comprising a pivoted arm, a rotary shaft, 95 cams carried by said shaft, a wabbling plate between said cams, a guide for said plate and means of connection between said plate and said arm, including a spring for moving the arm with a snap action when the 100 shaft is rotated.

6. Mechanism of the character described, comprising a frame having three bearing plates, a shaft supported by two of said plates, an arm pivoted to the third plate, a 105 wabbling member connected to said shaft and having a finger guided by said third plate and a spring connection between said finger and said arm.

WALTER A. BEHRENS.
